UNITED STATES PATENT OFFICE

125,220

DESIGN FOR A DRESS

Frances Troy Stix, New York, N. Y.

Application December 10, 1940, Serial No. 97,237

Term of patent 3½ years

To all whom it may concern:

Be it known that I, Frances Troy Stix, a citizen of the United States, residing at 169 East 78th Street, New York city, in the county of New York and State of New York, have invented a new, original, and ornamental Design for a Dress, of which the following is a specification, reference being had to the accompanying drawing, forming part thereof.

I claim:

The ornamental design for a dress, substantially as shown.

FRANCES TROY STIX.
